(57) **CLAIM**

The ornamental design for a sheet of glass, as shown and described.

DESCRIPTION

FIG. 1 is a top plan view of a sheet of glass showing our new design, the bottom plan view being a mirror-image of the top plan view shown;

FIG. 2 is a front elevational view thereof;

FIG. 3 is a left side elevational view thereof;

FIG. 4 is a right side elevational view thereof; and,

FIG. 5 is a rear elevational view thereof.

The side edges shown in phantom line and the color of the glass sheet are hereby disclaimed and form no part of the claimed design.
